UNITED STATES PATENT OFFICE.

JOSEPH W. WEINLAND, OF CHICAGO, ILLINOIS, ASSIGNOR TO AMERICAN STEEL FOUNDRIES, OF NEW YORK, N. Y., A CORPORATION OF NEW JERSEY.

BRAKE-BEAM SUPPORT.

1,206,066.

Specification of Letters Patent. Patented Nov. 28, 1916.

Application filed September 25, 1916. Serial No. 121,971.

To all whom it may concern:

Be it known that I, JOSEPH W. WEINLAND, a citizen of the United States, and resident of Chicago, in the county of Cook and State 5 of Illinois, have invented certain new and useful Improvements in Brake-Beam Supports, of which the following is a specification.

My invention relates to railway car brakes 10 and has particular reference to a novel emergency brake beam support. The construction here illustrated is intended as an improvement upon the construction shown in the patent to Elliott, No. 1,147,793.

15 A brake beam supporting means which provides for the suspension of a bar beneath the two brake beams has been found to be a most desirable and advantageous construction. However, it is necessary to provide 20 for the displacement of the bar by a longitudinal movement in either of two directions and to that end fastening devices, in the form of keys or cotters have been utilized. However, it has been found that the 25 wear due to the constant vibration causes the destruction of such fastening means. Not only that, but it is not uncommon that the key or cotter be lost or displaced by the workman when the bar has been removed, 30 or that the workman fails to return the key to its proper position through neglect or oversight.

With the object in view of overcoming the objections referred to, I have provided automatic means on the horizontal bar, or adapted 35 to coöperate therewith, which means cannot become lost and may be made of such size as not to be destroyed by wear due to vibration.

40 The invention will be more readily understood by reference to the accompanying drawings, wherein—

Figure 1 is a side elevation of a portion of a car truck, the side frame and wheels 45 being shown in dotted lines, and the brake beam and spring plank being shown in section; Fig. 2 is a sectional view on the line 2—2 of Fig. 1; Fig. 3 is a sectional view on the line 3—3 of Fig. 2, and Fig. 4 is an elevation of a slight modification in the construction shown in the preceding figure.

In the drawings the side frame is indicated at 10. Connecting the two frames necessary to constitute a truck is a spring plank 50 55 11 in the form of a channel. Near each end

of the channel I provide depending hangers 12, one at each side of the channel, the lower ends of the hangers being upset to form a shelf 15, the upper surface of which is in a plane with the bottom of an opening through 60 the hanger. The shelf provides a wide bearing for the supporting member 14. The construction of the hanger was not evolved by me, but will be claimed by another in a co-pending application. 65

The supporting bar 14 is in cross section in the form of an I-beam and is placed vertically, that is, with the web thereof extending vertically. As a fastening means I employ spring fingers or catches 15, riveted at 16 to the web of the bar and the points of which fingers or catches normally project outside a plane passing through the side edges of the flanges of the I-beam. By reason of this construction it will be seen that 70 the beam may be readily inserted by longitudinal movement into proper engagement with the hangers 12, a spring finger being depressed to the required extent. To remove the bar by a longitudinal sliding movement 75 thereof, it is only necessary to depress one of the springs 15. 80

In the modification shown in Fig. 4, the spring plank 17 and hanger 18 remain the same. In that instance I have provided a 85 leaf spring 19, which instead of being riveted to the bar is riveted to the hanger, and the lower end of which spring projects into the plane of the top of the bar. A notch 20 may be made in the top of the bar with 90 which the spring may engage. The operation of placing and replacing the bar will be readily understood without further description. 95

Obviously other forms of automatic fastening devices may be provided which will obviate the objections referred to and secure many, if not all, of the advantages of the constructions herein illustrated. My invention contemplates the use of such devices 100 and I therefore do not wish to be limited to the exact forms here shown and described.

I claim:

1. In an emergency brake beam support, the combination of a hanger, a bar supported by said hanger and longitudinally movable into and out of engagement therewith and automatic means acting as a lock to prevent relative movement of the hanger and bar, substantially as described. 105 110

2. In a car truck having frame members, the combination of a vertically disposed hanger engaging a frame member, a horizontally disposed bar engaging said hanger and spring means fixed to one of said members and automatically engaging the other thereof when the parts are in operative position, substantially as described.

3. In a device of the class described, the combination of a pair of depending hangers each having an aperture, a bar horizontally disposed and occupying the apertures in said hangers, and a spring fixed to said bar and adapted to automatically hold said bar when the same is in operative position, substantially as described.

4. In a device of the class described, the

combination of a hanger having an aperture, a bar adapted to be supported by said hanger and engaging said aperture, said bar having a side recess, a spring mounted in said recess, the end of which spring is adapted to normally project outside of the plane of the side of the bar, the arrangement being such that said spring acts as a fastening device, preventing longitudinal movement of said bar under normal conditions, substantially as described.

Signed at Chicago, Illinois, this 22nd day of September, 1916.

JOSEPH W. WEINLAND.
